CLAIM

The ornamental design for a table structure of a medical cart, as shown and described.

DESCRIPTION

FIG. 1 is a perspective view of table structure of a medical cart showing our new design;

FIG. 2 is a front view thereof;

FIG. 3 is a rear view thereof;

FIG. 4 is a right side thereof;

FIG. 5 is a left side view thereof;

FIG. 6 is a top plan view thereof;

FIG. 7 is a bottom plan view thereof;

FIG. 8 is an enlarged partial perspective view thereof;

FIG. 9 is an enlarged partial front view thereof;

FIG. 10 is an enlarged partial rear view thereof;

FIG. 11 is an enlarged partial right side view thereof;

FIG. 12 is an enlarged partial left side view thereof;

FIG. 13 is an enlarged partial top plan view of thereof; and,

FIG. 14 is an enlarged partial bottom plan view thereof.

The broken lines are included for the purpose of illustrating portions of the table structure of a medical cart that form no part of the claimed design.

1 Claim, 11 Drawing Sheets
